ELECTRIC COMMUNICATION NETWORK

Harry R. Allensworth, Columbus, Ohio

Application July 13, 1937, Serial No. 153,341

9 Claims. (Cl. 179—81)

This invention relates to a new and improved electric communication network and more particularly to a communication network, or that part of a communication network comprising a telephone transmitter, a telephone receiver, a transformer (induction coil) and two condensers (capacitors) and has for its object a new and improved combination of these elements in an electric network, functioning by means of electromotive force, the source of which electromotive force is external to the electric network comprising the said telephone transmitter, receiver, transformer and condensers.

A conventional telephone network comprises a three winding transformer, a transmitter, condenser and an inductively coupled receiver together with suitable switches and signaling and calling devices. The condenser and two windings of the transformer are in series—one of which two windings being connected across the terminals of the transmitter, directly on one side and in series with the condenser on the other. The third winding together with the receiver in series form an inductively coupled secondary circuit.

To my knowledge there has not been prior to this invention an electric communication network, telephonic or otherwise, comprising four transformer windings—three of said windings being primary to the fourth—a telephone transmitter, a telephone receiver, and two condensers; said network being divided into two parallel circuits bridged by one of said condensers.

The invention will be best understood from a consideration of the following detailed description taken in connection with the accompanying drawing forming a part of this application; with the understanding, however, that the invention is not confined to the one practical application herein selected for purposes of illustration nor is the invention confined to any strict conformity with the showing of the drawing which may be changed or modified so long as such changes and/or modifications mark no material departure from the salient features of the invention within the scope of the appended claims.

The accompanying drawing is a schematic delineation, by means of conventional symbols, of a useful and practical application of the invention in the form of a telephone subscriber's station network comprising eight members or parts to wit; a source of electromotive force—here represented by two sides of a line, L₁ and L₂; a telephone transmitter T; transformer windings P₁, P₂ and P₃; bridging condenser C; series condenser C₁ and an inductively coupled secondary circuit comprising transformer winding S and telephone receiver R. Also are shown, by means of conventional symbols, calling device CD with

associated shunt contacts SH, polarized ringer or bell B and hook switch HS with associated contact springs 8 and 9. Calling device CD with associated shunts, ringer B and hook switch HS are not, per se, a part of the invention. Calling device CD with associated shunt contacts is shown for the purpose of revealing certain important characteristics of the network. Hook switch HS and polarized ringer B are shown for the purpose of explaining the function and action of contact springs 8 and 9.

The source of electromotive force L₁ and L₂ may be a telephone line terminating in a common battery telephone switchboard or other common battery switching mechanism—it may be a circuit to another telephone not connected to or with an exchange system, in which case electromotive force is impressed on the circuit at some convenient point external to the network herein described—it may be a telegraph or other signal circuit—it may be any suitable electric circuit which it may be practicable to employ for telephonic purposes by means of the network herein described.

Electromotive force from the source L₁ and L₂ is impressed on the circuit or network at points 4 and 5 causing electric current to flow through P₂, T. The divided circuit 4, P₁, C₁, P₃, 5; 4, P₂, T, 5 is bridged by a condenser C at points 6 and 7.

All four transformer windings P₁, P₂, P₃ and S are on the same magnetic core.

The operation of this circuit or network during speech transmission is as follows.

The line circuit L₁, L₂ which supplies direct current from a central office battery or other suitable source, divides into two parallel circuits at points 4 and 5; one of the two parallel circuits comprising transmitter T and P₂ in series—the other, comprising P₁, C₁ and P₃ in series. Battery flows in that branch of the divided circuit comprising P₂, T; the other branch of the divided circuit being "open" to direct current because of condenser C₁ being in series with P₁ and P₃.

Another circuit, local to the network, in the form here shown, comprises transmitter T, condensers C and C₁ and transformer winding P₃. It should be noted however, that the position of condenser C₁ is not fixed by either this description or the drawing herein. Condenser C₁ may be placed at any convenient and practical point in that branch of the divided circuit defined by 4, P₁, 7, P₃, 5.

When the transmitter T functions in response to sound waves, corresponding potential undulations are produced directly in the line through transmitter T and winding P₂. Condenser C is connected across the terminals of transmitter T directly on one side and through condenser C₁ 60

and winding P_3 on the other. Condenser C charges and discharges due to varying potential drop across transmitter T . This causes P_3 and P_1 to function as an auto transformer in which circumstance P_1 is secondary to P_3 . The current flowing in the said local circuit divides at the point 7 ; part flowing through C_1 , P_3 and part through P_1 . Thus the inductive effect of P_3 on S is neutralized more or less depending on the relative proportions of P_1 , P_2 and P_3 ; an effect known to the art as "anti-sidetone". Also, P_1 functions as an inductively coupled feed back on P_2 producing improved booster characteristics in the network. As herein before stated, C_1 may or may not be comprised in said local circuit.

When the transmitter at the distant station functions, potential undulations from L_1 and L_2 are impressed at points 4 and 5 which causes undulatory current to flow in P_2 , T and corresponding alternating current to flow in P_1 , C_1 , P_3 in which circumstance P_1 , P_2 and P_3 are primary to S and corresponding alternating E. M. F. is induced in S causing alternating current to flow in S and receiver R .

When calling device CD is operated—associated shunt contacts SH close, shunting transmitter T and transformer winding S . Inasmuch as S is secondary to P_1 , P_2 and P_3 —shunting S during the operation of CD lessens the impedance of P_1 , P_2 and P_3 to current impulses produced by CD .

Condenser C is shown bridging the network at points 6 and 7 . Condenser C_1 is shown in series relation with P_1 and P_3 . It is not necessary to employ two separate condensers in the network. C and C_1 may be, in some instances, two sections of a dual condenser.

When hook switch HS is down contact springs 8 and 9 put C in series with B across L_1 and L_2 . When HS is up C , by means of 8 and 9 , bridges the network at points 6 and 7 as is shown.

Thus the said eight members or parts as assembled and combined in the invention effect the following improved results over other such networks; lessened impedance to dialing impulses, improved booster effect together with anti-sidetone characteristics and high fidelity transmission and reception.

What is claimed is:

1. An electric communication network comprising two parallel circuits, one of the two parallel circuits comprising a telephone transmitter in series relation with one winding of a transformer having four windings, the other of the said parallel circuits comprising two of said windings and a condenser in series relation therewith and a condenser bridging said circuits from a point between the transmitter and transformer winding in one of said parallel circuits to a point between the two transformer windings in the other of the said parallel circuits.

2. An electric communication network comprising two parallel circuits, one of the two parallel circuits comprising a telephone transmitter in series with one winding of a transformer having four windings and the other of the said parallel circuits comprising two of said windings and a condenser in series relation therewith; the said three windings in the said parallel circuits being primary to said fourth winding.

3. An electric communication network com-

prising two parallel circuits, one of the said parallel circuits comprising a telephone transmitter in series with one winding of a transformer having four windings; the other of the two parallel circuits comprising two of said windings and a condenser in series, and a telephone receiver in series with said fourth winding forming an inductively coupled circuit, secondary to the three said transformer windings.

4. An electric communication network in which both anti-sidetone and booster characteristics are incorporated by dividing the said circuit or network into two parallel circuits, one of which parallel circuits comprises a telephone transmitter in series with one winding of a transformer having four windings, the other of which parallel circuits comprises two of said windings and a condenser in series relation therewith, and a condenser bridging said circuits at points of approximately equal potentials.

5. An electric communication network comprising two parallel circuits, one of the two parallel circuits comprising a telephone transmitter in series with one winding of a transformer having four windings, the other of the said parallel circuits comprising two of said windings and a condenser in series, the total impedance offered by said parallel circuits to pulsating current set up in said network being reduced by short circuiting a transformer winding said short circuited transformer winding being secondary to the three said transformer windings comprised in the said two parallel circuits.

6. An electric communications network comprising a transformer having four separate windings, three of said windings being primary to the fourth, two parallel circuits, a condenser bridging said parallel circuits and a condenser in one of said parallel circuits in series with two of the aforesaid windings.

7. An electric communication network comprising two parallel circuits and a transformer having four windings, one of said parallel circuits comprising a telephone transmitter and one of said transformer windings in series relation therewith, the other of the two parallel circuits comprising two of said windings and a condenser in series relation therewith, said parallel circuits comprising a local circuit including said telephone transmitter.

8. An electric communication network comprising two parallel circuits and a transformer having four windings, one of said parallel circuits comprising a telephone transmitter and one of said transformer windings in series relation therewith, the other of the two parallel circuits comprising two of said windings and a condenser in series relation therewith, a condenser bridging said parallel circuits; said parallel circuits comprising a local circuit including said telephone transmitter and said bridging condenser.

9. An electric communication network comprising two parallel circuits and a condenser bridging said circuits, one of the two parallel circuits comprising a telephone transmitter in series with one winding of a transformer having four windings, and one of said parallel circuits comprising a condenser and two of said windings in series, the three windings in the said parallel circuits being primary to a fourth connected directly to a telephone receiver.

HARRY R. ALLENWORTH.
